(57) **CLAIM**

The ornamental design for a bed tent, as shown and described.

DESCRIPTION

FIG. 1 is a front and top side perspective view of a bed tent in accordance with my new design;

FIG. 2 is a right side elevational view thereof, the left side elevational view being identical thereto;

FIG. 3 is a top plan view thereof;

FIG. 4 is a bottom plan view thereof;

FIG. 5 is a front elevational view thereof; and,

FIG. 6 is a rear elevational view thereof.

The broken lines in the figures are directed to environment and are for illustrative purposes only; the broken lines form no part of the claimed design.

1 Claim, 3 Drawing Sheets

FIG. 3

FIG. 4

FIG. 5

FIG. 6
